UNITED STATES PATENT OFFICE.

GEORGE H. HULETT, OF CLEVELAND, OHIO, ASSIGNOR, BY MESNE ASSIGNMENTS, TO THE McMYLER CAR-DUMPING MACHINE COMPANY, OF SAME PLACE.

PORTABLE DEVICE FOR UNLOADING CARS.

SPECIFICATION forming part of Letters Patent No. 536,209, dated March 26, 1895.

Application filed February 1, 1894. Serial No. 498,769. (No model.)

To all whom it may concern:

Be it known that I, GEORGE H. HULETT, of Cleveland, in the county of Cuyahoga and State of Ohio, have invented certain new and 5 useful Improvements in Portable Devices for Unloading Cars; and I do hereby declare the following to be a full, clear, and exact description of the invention, such as will enable others skilled in the art to which it appertains to 10 make and use the same.

My invention relates to an improvement in portable devices for unloading railroad cars, and is designed more particularly as an improvement on the construction disclosed in 15 my Patent No. 516,053, granted March 6, 1894.

My present improvements consist more particularly in improved means for operating the discharging trough through which the coal or other material is discharged; in means for re- 20 moving the end or end gate of the car, and in means for preventing the coal or other material from falling out at the sides during the operation of tilting the car.

In the accompanying drawings, Figure 1 is a view in side elevation of my improved device showing a car thereon, the cylinders and plungers for operating respectively, the trough of the platform and end gate of the car, being omitted. Fig. 2 is an enlarged view 25 of the shorter end of the tilting platform showing the trough in dotted lines, the hydraulic devices for actuating the same, and the devices for elevating the end gates of the cars the operator's cage being omitted. Fig. 3 is a view in cross section of the tilting platform showing the trough therein, and Fig. 4 is a transverse sectional view of the shield. 30

A represents a railway constructed to receive the truck B, which latter is mounted on 35 wheels C arranged in pairs and is adapted to travel back and forth parallel to the pier or water front, as shown, or parallel to bins or other repositories designed to receive coal or material usually carried in bulk. The wheels 40 C are as stated arranged in pairs, each pair constituting in effect a truck, the trucks so formed being pivotally connected to the main truck B, so as to enable the wheels to follow inequalities in the track without straining the 45 parts. This truck B is provided on its upper

face with a bearing or way for the rollers D, which latter are carried by the ring E. Resting on the rollers D, and secured to the truck by a suitable king bolt or equivalent device is the rotary platform F, which latter carries a suitable engine and boiler, or electric or other motors for actuating the drums and other movable parts. The platform is rotated by means of the rack and pinion ordinarily employed for that purpose, and is provided with the uprights F' and G, the former being considerably longer or higher than the latter and connected thereto by the braces G', G". 55

The two shorter uprights G are connected together at the tops and at intermediate points 60 if desired, while the uprights F' are also connected at their tops by the braces G". 65

Pivotedly mounted on the upper ends of the shorter uprights G is the inclined platform H, which latter consists of preferably two parallel girders G⁴ (see Fig. 3) located a proper distance apart and connected at intervals through their length, forming in effect a platform. The platform thus formed is provided with rails, G⁵, (see Fig. 1) and is beveled at the 70 end of its longer arm (not shown) so that when in position the beveled ends of the rails will rest on the rails of the surface track and form a continuation thereof, so that a car on the surface track can, by the mechanism to 75 be hereinafter described, be drawn up the inclined platform to the position shown in Fig. 1, discharged of its contents and lowered onto the same or onto another track.

The platform H is pivoted to one side of the 80 center, and is provided at its outer or shorter end with a bumper or buffer I and adjacent to the latter is the mouth of the discharging chute J. The chute J is open at its bottom, and discharges directly into trough J⁸, the 85 shape of which is clearly shown in Fig. 3. This trough is open at its top and is provided with flanged rollers a at intervals along both sides of its bottom which run on the flanges b of the angle irons c constituting parts of the 90 girders, and is provided on its opposite sides near its upper edge with flanged rollers d which are designed to move in contact with the lower faces of the angle irons c also constituting parts of the girders. 95

Secured to the under side of the trough are the plates *e*, to which is secured the free end of the plunger *f*. This plunger is carried by the hydraulic cylinder *g*, which latter is supported at intervals by the beams *h* secured to the under side of the girders which constitute the body of the tilting platform. Water under pressure directly from pumps or from an accumulator (not shown) on the rotary platform is conveyed through flexible or telescopic pipes or by any other of the well known means in common use to the cylinder *g* at a point in front of the plunger head, and operates to govern or control the outward movement of the trough, hold it in any desired position and restore it to its normal position within the tilting platform as shown in Figs. 1 and 2. If desired, water can also be introduced behind the plunger head so that the trough can be forcibly pushed out in the event of clogging or if the weight of the coal should be insufficient. After the platform has been tilted and a portion of the coal or other material discharged into the chute and from the latter to the trough, the weight of the coal tends to force the trough outwardly. Hence by releasing the water in front of the plunger the trough will descend by gravity and can be stopped by simply shutting off the water, and elevated by admitting water under pressure. In this device, as in the patent hereinbefore referred to, the trough is provided with gates at its end and one in its bottom through which the coal can be discharged, the gates when open acting as deflectors for the coal.

Located under and carried by the the tilting platform is a second hydraulic cylinder *h'* (see Fig. 2) the plunger of which is connected to chain *i*. This chain *i* passes along the under side of the tilting platform to the sheave *j* and from thence up to the small winding drum *k* on the operator's cage *l*. This drum *k* carries two larger drums *m* around which chains *n* are wound, the chains *i* and *n* being passed around their drums in opposite directions so that when one is wound the other will unwind and vice versa. Chains *n* carry hooks or other devices for engaging the end gate of the car for elevating same.

Water under pressure is admitted on both sides of the plunger head in cylinder *h'*, and is conveyed to said cylinder through flexible or other pipes, and the movements of this plunger and also the plunger which actuates the trough are under the control of the operator located in cage *l*. By admitting water to both sides of the plunger head in cylinder *h'* chains *n* carrying the gate hooks can be elevated or lowered at the will of the operator.

The operator's cage *l* is located at the outer end of the shorter arm of the platform in a position over the chute. Pivoted to the operator's cage at the point *a*⁶, or at the top of the buffer is one end of the shield or frame *P*, the opposite end being supported by rods

o which engage the girders *G*² as shown in Fig. 1, thus leaving the shield free to accommodate itself to the top of the car and supporting the shield when the car is removed. This shield *P* is designed to occupy a position above the car and is preferably open on top, the two sides or two frames being connected by yokes *p*. These frames form in effect continuations of the sides of the car, and prevent the coal from rolling off at the sides while the car is being tilted.

The trough directs the coal or other contents of the car to any part of the hold or bin, and the gates at the end thereof are actuated by ropes or chains under the control of the operator whereby the discharge can be regulated both as to quantity and direction.

After the car has been discharged of its load, the platform is tilted so as to carry the end thereof well out of the hold or bin, and the rotary platform is then turned so as to bring the beveled end of the tilting platform over a track onto which the empty car is to be run. The platform is then lowered onto said track and the empty car lowered, after which the platform is turned to the track having the loaded cars thereon, and another one carried up and discharged as described.

Is a hydraulic cylinder pivotally or loosely mounted on truck *B* and provided with a plunger, the free end of which is connected to the tilting platform as shown. By means of this plunger and suitable means for forcing water therein the tilting platform can be tilted from the position shown in Fig. 1 so as to bring the discharge end well down over the boat. By permitting the water to escape from the hydraulic cylinder the opposite end of the platform is lowered onto the track.

The platform *H* is provided with a sheave *H'*, around which passes chain *M*. The free end of this chain is adapted to be attached to the car coupler, while the opposite end thereof is secured to drum *N* after passing around sheaves *N*² *N*³. Thus when the platform is in the position shown in Fig. 1, and the chain *M* attached to a car the rotation of the drum *N* which is actuated by a suitable motor causes the car to move up the incline until it comes in contact with the buffer. The drum is then locked against rotation, and the platform tilted by the mechanism previously described.

By mounting the tilting platform on a truck the entire apparatus can be moved lengthwise the vessel so as to bring the discharging end thereof over the several hatchways, thus permitting the entire cargo to be stored without shifting the boat.

Instead of employing hydraulic devices for tilting the platform chains can be employed.

I would have it understood that I do not confine myself to details of construction, but consider myself at liberty to make such changes and alterations as fairly fall within the spirit and scope of my invention.

Having fully described my invention, what I claim as new, and desire to secure by Letters Patent, is—

1. In a portable device for unloading cars, the combination with a truck a rotary platform thereon, and a tilting platform carried by the rotary platform, of a buffer near the discharge end of the tilting platform, a chute through which the material passes, a slideable trough carried by the tilting platform and communicating with the chute, and hydraulic devices for actuating said sliding trough substantially as set forth.
2. The combination with a lengthwise tilting platform pivoted at a point between its ends and provided with a track on which cars may be run and supported, of a shield pivoted to the tilting platform and extending lengthwise the car and adapted to rest over and in close proximity to the sides of the car, substantially as and for the purpose set forth.
3. The combination with a truck, a rotary platform thereon and a lengthwise tilting platform pivoted at a point between its ends to the rotary platform, of a shield attached to the tilting platform and extending lengthwise

over the car, the said shield resting approximately over the upper side edges of the car, and a buffer adjacent to the pivoted end of the shield, against which the car abuts when 30 in position to discharge its contents.

4. In a portable device for unloading cars, the combination with a truck and a rotary platform thereon, of a tilting platform carried by the rotary platform, a buffer and chute 35 on said tilting platform and means carried by said tilting platform for elevating and lowering the end gate of the car.

5. In a portable device for unloading cars, the combination with a truck and a rotary 40 platform thereon, of a tilting platform carried by the rotary platform, a buffer and chute on said tilting platform, and an operator's cage located adjacent to the buffer and chute, substantially as set forth.

In testimony whereof I have signed this specification in the presence of two subscribing witnesses.

GEORGE H. HULETT.
